VACUUM INLET

James F. Anderson, Grand Rapids, Mich., assignor to
Ander-Mel, Incorporated, Wyoming, Mich.

Filed Mar. 9, 1973, Ser. No. 339,706

Term of patent 14 years

Int. Cl. D8—99

U.S. Cl. D8—187

FIG 1

FIG 5

FIG. 2

FIG. 4

FIG. 3

FIG. 1 is a perspective view of the vacuum inlet;
 FIG. 2 is a top plan view of the vacuum inlet shown in FIG. 1;

FIG. 3 is a side elevation of the vacuum inlet shown in FIG. 2;

FIG. 4 is a cross-sectional, side elevation of the vacuum inlet of FIGS. 1, 2 and 3, taken along plane 4-4 of FIG. 2; and

FIG. 5 is a cross-sectional view taken on the line 5-5 of FIG. 2.

I claim:
 The ornamental design for a vacuum inlet, substantially as shown and described.
